LETTER AND NAME GAME APPARATUS

Ivy M. Hill, 285 King George Terrace,
Victoria, British Columbia, Canada
Filed Aug. 4, 1964, Ser. No. 387,456
2 Claims. (Cl. 273—135)

ABSTRACT OF THE DISCLOSURE

Game board apparatus including a board with squares laid out thereon in columns and having category playing pieces to be placed on marked category areas associated with said columns, each piece bearing the name of a category, some of said areas being associated with a single column and others associated with a plurality of columns, and a plurality of initial playing pieces each containing an alphabetical letter and an evaluation number thereon, said initial pieces being adapted to be selectively placed on squares in columns associated with selected category playing pieces on category areas.

This invention relates to letter and name game board apparatus.

An object of the present invention is the provision of a game apparatus which may be used and enjoyed by persons of all ages for both educational and amusement purposes.

Another object is the provision of game board apparatus which will help the players to develop their thinking and reasoning powers, and to increase their knowledge along desirable lines.

This game can be played and enjoyed by one or more players, since each person is playing against himself, that is, against his own knowledge and thinking power, as well as against other players. The game lends itself to be played in a comparatively simple form, and in more complex or difficult forms. It includes a game board having a plurality of marked category areas located side by side thereon, and at least one column of squares substantially aligned with each area. A plurality of category playing pieces each containing at least one name are used, as well as a plurality of initial playing pieces each containing a letter and an evaluation number. If desired, one or more blank playing pieces and/or one or more generic playing pieces each with an evaluation number thereon may also be provided.

Game apparatus according to the present invention is illustrated in the accompanying drawings, in which:

FIGURE 1 is a reduced plan view of the game board,

FIGURE 2 illustrates some of a plurality of initial playing pieces,

FIGURE 3 illustrates examples of category playing pieces,

FIGURES 4 and 5 illustrate other forms of category playing pieces,

FIGURE 6 shows two blank playing pieces, and

FIGURE 7 illustrates a generic playing piece.

Referring to the drawings, 10 is a game board formed of suitable material, such as cardboard, and having a playing area 11 located centrally thereof and surrounded by a border 12 along the edges of the board. The illustrated board 10 is set up for three variations of this game, but it is to be understood that it may be set up for one variation or any combination of these variations. In this example, a plurality of first category areas 16 are located side by side in border 12 along one edge of the board. There may be any desired number of these category areas, but in this example there are six areas 16, and these are marked S-1 to S-6 for convenience. The playing area 11 is marked off in a plurality of squares

2

18. It will be noted that there is a horizontal column 19 of squares 18 associated and aligned with each category area 16 and extending inwardly from said area and across area 11.

5 A second set of category areas 22 is located in border 12 along another side of board 10. In this example, there are three areas 22 marked D-1, D-2 and D-3. There are two vertical columns 23 of squares 18 associated and substantially aligned with each category area 22 and extending inwardly of the board from the latter area.

10 Board 10 also has a third set of category areas 26 in border 12 along a third side of the board, there being two of these illustrated and marked T-1 and T-2. There are three horizontal columns 27 of squares 18 associated and substantially aligned with each category area 26 and extending inwardly of the board from the latter area.

15 FIGURE 2 illustrates a plurality of initial playing pieces 30, each containing a letter 31 and an evaluation number 32. These playing pieces may be made of cardboard, wood, plastic or the like, and there may be any number of them, for example, 60 pieces. These preferably include all of the letters of the alphabet, and, if desired, some may include two letters, such as "Q/Z" and "U/X." The following is an example of the number of initial pieces that will make up a good game, the lettering of these pieces and the evaluation numbers thereof:

2—A-15	4—M-5
3—B-10	2—N-15
3—C-10	1—O-20
3—D-10	3—P-10
2—E-15	1—Q/Z-25
3—F-10	3—R-10
3—G-10	4—S-5
3—H-10	3—T-10
1—I-20	1—U/X-25
2—J-15	1—V-20
2—K-15	3—W-10
3—L-10	1—Y-20

20 FIGURE 3 illustrates a plurality of category playing pieces 35 that are particularly for use with the singles category areas 16 of the game board. Each category piece 35 includes the name of a group of articles, animals, flowers, countries, cities, and the like. A good game is provided if there are 16 of these category playing pieces containing names such as follows:

Animals	States
Birds	Cities
Flowers	Towns in Home
Trees	State
Lakes	Car Makes
Rivers	Occupations
Mountains	Games and
Vegetables	Sports
Countries	Nationalities

25 FIGURE 4 illustrates a plurality of category playing pieces 38 which are intended to be used with the doubles category areas 22. Each playing piece 38 includes names of objects, places, entertainers, brand names, statesmen, or the like that may be in two words. A good game is developed if there are 12 of these doubles category pieces 38, containing the following names:

Characters	TV stars
Place names	Movie stars
Brand names	Relatives
Titles	Statesmen
Entertainers	Sports figures
Singers	Writers

30 FIGURE 5 illustrates a plurality of category playing

pieces 42 particularly designed for use with triples category areas 26 of the game board. Playing pieces 42 include names which may comprise three words. There may be four of these triple playing pieces containing the following names:

Abbreviations	Famous persons
Organizations	Titles

Further variety may be incorporated into the game by providing a plurality of blank playing pieces 45, as shown in FIGURE 6, and/or one or more generic or "joker" playing pieces 47. Pieces 45 may have zeros 46 thereon representing no value, while each playing piece 47 may have an evaluation number 51.

The method of playing the games may be varied in a number of ways, but in each case the basic elements of the games have to be used. The games may be played by any number of individuals, or by teams of individuals. The "singles" game means that single words are used, the "doubles" game means that double words and letters or initials are used, and the "triples" game means that triple words and letters or initials are used.

Starting with a "singles" game, the players in order select six category playing pieces 35 and place them on the six category areas 16. Each player picks up or draws six initial playing pieces 30 without seeing the letters or evaluation numerals thereof. The first player tries to play his pieces 30 on squares 18 in the column 19 aligned with each of the six category pieces on the category areas. For example, if the category piece 35 on S-1 has "animals" on it, the player tries to name an animal, the first letter of the name of which appears on one of his initial pieces 30. For example, if he has a playing piece with the letter "C" on it, he could place it under the "animals" playing piece and call out "cat." If he is not able to place all of his pieces 30 across the board under the six category pieces, he retains the playing pieces not so placed, and these will count against him by the amounts indicated by each one. Each succeeding player attempts to do the same thing, placing his pieces 30 on the squares 18 beside those placed on the board by the first player. When all the players have had a turn, they then draw six more initial pieces 30, and this is continued until each player has a predetermined number of turns. At the end, each player totals the numbers on the initial pieces he was not able to place on the board during each turn, and the player who has the lowest score wins the game.

The procedure for the "doubles" game is the same as that for the "singles" game. In this case, however, category playing pieces 38 are placed on the category areas 22 which are marked D-1, D-2 and D-3. In this case, the initial pieces 30 are placed in pairs in the columns 23 aligned with each category piece 38. For example, if the category piece has "place names" on it, the player has to call a place name involving two words beginning with letters for which he has initial pieces 30. For example, if he has two pieces 30 with the letter C on them, he could call out "Corpus Christi," and lay his two pieces down in the appropriate columns on the board.

The "triples" game is played in the same manner as the others, excepting that category pieces 42 are placed on the category areas 26 which are marked T-1 and T-2. In this case, the player must play three initial pieces 30 each time, placing said pieces in the appropriate columns 27 aligned with the category piece with which he is working. For example, if the category piece 42 has "famous persons" on it, he could name "J. B. Brown" if he had initial pieces with the letters J. B. B. on them.

The blank pieces 45 may be used, and these are most welcome to a player since he can play them on any desired square. For example, in a "singles" game he can play a blank piece under the hardest category to fill, while in "doubles" or "triples" games he can play the blank only with one or two initial pieces respectively. If

a player draws a generic piece 47, he can use it as any desired letter, but if he cannot get rid of it by playing it on the board, he has a large count, namely 50, against him.

The actual equipment of this game is relatively simple, but a great deal of enjoyment can be had with this game, while the players improve their thinking ability and knowledge on various subjects. The game can be played by a single person since he is playing against himself, or against his ability to think up names and words to fit each situation in which he finds himself. On the other hand, several players can play in competition with each other.

What I claim as my invention is:

1. Educational game apparatus comprising, in combination:
  - (a) a board having a plurality of side edges,
  - (b) a plurality of unmarked squares on the board formed by intersecting, equally spaced, parallel, vertical and horizontal lines, said squares being arranged by said lines in columns perpendicular to the board side edges,
  - (c) a plurality of first marked category areas side by side on the board along a first of said side edges, one of said columns of squares being associated with and extending inwardly of the board from each first category area,
  - (d) a plurality of first category playing pieces each adapted to be placed on a first category area and containing a category name,
  - (e) a plurality of second marked category areas side by side on the board and along a second of said side edges, two adjacent of said columns of squares being associated with and extending inwardly of the board from each second category area, and each second category area extending on opposite sides of the line between the two columns of squares associated therewith,
  - (f) a plurality of second category playing pieces each adapted to be placed on a second category area and containing a designation of a category with names comprising two words,
  - (g) a plurality of third marked category areas side by side on the board and along a third of said side edges, three adjacent of said columns of squares being associated with and extending inwardly of the board from each third category area,
  - (h) a plurality of third category playing pieces each adapted to be placed on a third category area and containing a designation of a category with names comprising three words,
  - (i) a plurality of initial playing pieces each containing an alphabetical letter and an evaluation number, said initial pieces being adapted to be selectively placed on squares in columns associated with selected category playing pieces on the category areas of the last-mentioned columns.

2. Game apparatus as claimed in claim 1 including a plurality of playing pieces having zero evaluation, and a plurality of "joker" generic playing pieces having an evaluation number thereon, said zero and generic playing pieces being similar to said initial pieces and being adapted to be selectively placed on squares in the same manner as the initial pieces.
